United States Patent Office.

R. H. FISHER, OF BEAVER FALLS, PENNSYLVANIA.

Design No. 3,108, dated July 14, 1868.

DESIGN FOR A KNIFE-HANDLE.

The Schedule referred to in these Letters Patent and making part of the same.

TO ALL WHOM IT MAY CONCERN:

Be it known that I, R. H. FISHER, of Beaver Falls, in the county of Beaver, and State of Pennsylvania, have invented a new and useful and original Design for Handles for Table-Knives; and I do hereby declare the following to be a full, clear, and exact description thereof, reference being had to the accompanying drawing, making a part of this specification, in which—

Figure 1 is a perspective view of a table-knife, showing my improved design for the handle, and

Figure 2 is a cross-section of the knife-handle shown in fig. 1, through the line *x x*.

Like letters of reference indicate like parts in each.

My improved design for the handles of knives for table-use, consists in grooved or fluted sides in handles diminishing in width toward the end and toward the blade.

That the character of my invention may be more readily understood, I will proceed to describe the same.

a is the blade of a common table or case-knife, which, with its handle, *b*, is made from a single piece of steel. The width of the handle *b* diminishes from its broadest part, *c c*, each way, both toward the end and toward the blade. The sides of the handle are deeply grooved or fluted as at *d d*, but not so deeply but that a thin lamina of metal, *e*, will separate them. In this way I make a neat, ornamental handle, one which is not too heavy for convenient use, and a knife and handle which are durable and substantial. The handle should, however, be plated with silver or other metal or metals which will prevent oxidation.

What I claim as my invention, and desire to secure by Letters Patent, is—

The design for handles for table-knives herein set forth and shown.

In testimony whereof, I, the said R. H. FISHER, have hereunto set my hand.

R. H. FISHER.
